[57] CLAIM

The ornamental design for a rear view mirror, substantially as shown and described.

DESCRIPTION

FIG. 1 is a rear elevational view of a rear view mirror embodying my new design;

FIG. 2 is an elevational view of one end thereof;

FIG. 3 is a front elevational view thereof;

FIG. 4 is a top plan view thereof;

FIG. 5 is a top plan view of the mounting bracket thereof, taken at line 5—5 of FIG. 3;

FIG. 6 is an elevational view of the other end thereof; FIG. 7 is an elevational view of the rear view mirror in an alternate position as installed on a vehicle body, it being understood that the broken lines are for illustrative purposes only;

FIG. 8 is a bottom plan view of the head of the mirror, taken at line 8—8 of FIG. 7; and

FIG. 9 is a bottom plan view thereof.
